UNITED STATES PATENT OFFICE

110,146

DESIGN FOR A FOUNTAIN SHELF RACK

George B. Hume, Kansas City, Mo.

Application April 6, 1938, Serial No. 76,324

Term of patent 14 years

To all whom it may concern:

Be it known that I, George B. Hume, a citizen of the United States, residing at Kansas City, Jackson County, Missouri, have invented a new, original, and ornamental Design for a Fountain Shelf Rack of which the following is a specification, reference being had to the accompanying drawing, forming a part thereof.

The figure is a perspective view of a fountain shelf rack, showing my new design.

I claim:—

The ornamental design for a fountain shelf rack, as shown.

GEORGE B. HUME.
